John H. Farley

UNITED STATES PATENT OFFICE

PETER J. LUNATI, OF MEMPHIS, TENNESSEE

AUTOMOBILE SERVICING LIFT

Application filed August 16, 1926. Serial No. 129,529.

This invention relates to automobile-servicing lifts and is an improvement over my prior Patent No. 1,552,326, and my copending applications Serial Nos. 36,019, filed March 6th, 1926, (Patent No. 1,689,144, October 23, 1928) and 86,569 filed April 8th, 1926, (Patent No. 1,689,145, October 23, 1928).

In my prior patent and copending applications above referred to I have disclosed a cylinder adapted to be suitably supported in a concrete base embedded in the ground. A hollow plunger piston reciprocates in the cylinder and is provided at its upper end with vehicle supporting rails which normally are arranged in proximity to the ground to permit a vehicle to be driven thereon. The interior of the plunger communicates at its lower end with the interior of the cylinder and means is provided for introducing fluid pressure into the interior of the plunger to effect the elevation thereof. In the prior constructions referred to the upper end of the plunger reciprocates in a bearing carried by the cylinder and provided with suitable packing to prevent the escape of fluid pressure. A relatively small cap is provided at the lower end of the plunger which has a relatively small bearing surface contacting with the interior wall of the cylinder to maintain the plunger in proper alignment. In the prior constructions, the vehicle supporting rails were secured to the plunger by mounting them upon supporting arms arranged in a shallow pit in the ground to permit the vehicle rails to be brought downwardly into contact with the ground. It has been found that the surrounding ground or suitable concrete platform usually is not perfectly level, and accordingly one portion of the rails contacts with the ground before other parts, and accordingly there is a tendency for the weight of the vehicle, particularly when not properly centered over the plunger, to cause the plunger to swing out of alignment thus greatly increasing the friction between the lower piston cap and the interior of the cylinder and tending to unevenly wear the bearing at the upper end of the cylinder. In the prior constructions there also was a tendency for the fluid pressure to

leak past the packing provided at the upper end of the cylinder.

An important object of the present invention is to provide a hydraulic lift of the type disclosed in my patent and copending applications above referred to wherein the construction is rendered cheaper to manufacture and at the same time more efficient in operation.

A further object is to provide a structure wherein friction is materially reduced under all conditions, and particularly when the vehicle is not accurately centered over the plunger.

A further object is to provide a hydraulic lift construction wherein damage to the upper cylinder bearing is eliminated when the device is employed upon uneven surfaces.

A further object is to provide a device of the above mentioned character provided with means having a fluid seal between the interior of the cylinder and the cylinder packing when the plunger is in its extreme upper position, thus relieving the packing from pressure and eliminating leakage therethrough.

A further object is to provide an improved form of vehicle supporting means whereby the shallow pit previously provided for the rail supporting arms is eliminated.

A further object is to provide an improved hydraulic lift construction wherein the upper portion of the cylinder may be removed to permit removal of the plunger without the necessity of removing the cylinder from its concrete base.

Other objects and advantages of the invention will become apparent during the course of the following description.

In the drawings I have shown one embodiment of the invention. In this showing,

Figure 1 is a central vertical longitudinal sectional view showing the device in lowered position,

Figure 2 is a plan view,

Figure 3 is a section on line 3—3 of Figure 2, and,

Figure 4 is an enlarged central vertical sectional view of the lower end of the cylinder and associated elements.

Referring to the drawings the numeral 10

- designates a suitable cylinder preferably formed of steel pipe or the like enclosed by a lower head 11 preferably secured in position by welding. The cylinder is embedded 5 in a well or base of concrete 12, and the surface of the ground also is preferably concreted as at 13. The cylinder is provided at its upper end with an outstanding flange 14 for a purpose to be described.
- 10 A bearing 15 is arranged over the upper end of the cylinder and forms in effect a part thereof. The bearing 15 is provided at its lower end with an outstanding flange 16 which is bolted or otherwise secured as at 15 17 to the flange 14. Packing 18 is arranged in the upper end of the bearing 15 and a packing gland 19 is bolted to the bearing 15 as at 20 whereby the packing is pressed in the usual manner.
- 20 The plunger 21 is mounted to reciprocate within the cylinder as shown in Figure 1, the plunger preferably being formed of steel piping and polished on its outer surface whereby it is adapted to slide within the bearing 15. The lower end of the plunger 21 is provided with a sleeve 22 preferably welded thereto and extending a substantial distance downwardly therefrom. The plunger is provided with a lower head 23 25 preferably welded to the sleeve 22 and provided with a relatively large central opening 24 for a purpose to be described. A thimble 25 is mounted in the opening 24 as shown in Figure 4. This thimble is provided with a cylindrical portion 26 which extends through the opening 24, and the cylindrical portion is provided with a preferably integral lower horizontal flange 27. An upper flange 28 is secured to the cylindrical portion 26 and is provided with a series of openings 29 arranged inwardly of the opening 24, as shown in Figure 4. The plunger is closed at its upper end by a head 30 as shown in Figure 1.
- 45 The cylinder and plunger are adapted to contain a body of oil substantially to the level indicated by the dotted line 31 in Figure 1, when the plunger is in its lower position. Means are provided for introducing 50 fluid pressure into the interior of the plunger above the level of the oil therein. As shown, a vertical pipe 32 is arranged centrally within the plunger and cylinder and has its upper end projecting a slight distance 55 above the level of the oil. The lower end of the pipe is threaded into the cylinder head 11 as at 33 whereby the pipe is carried by the cylinder and is fixed against movement. An elbow 34 also is threaded in the head 11 and 60 communicates with the pipe 32. A horizontal pipe 35 is connected at one end to the elbow 34 and at its opposite end to a vertical pipe 36 preferably embedded in the concrete well 12. The pipe 36 communicates at 65 its upper end with a horizontal pipe 37 ar-
- ranged beneath the surface of the ground. A vertical pipe 38 is connected at its lower end to the pipe 37 and is provided at its upper end with a T-joint 39. This joint connects at one side to an exhaust valve 40 and 70 at its opposite side the joint is connected to an inlet valve 41, both of the valves being manually controlled as will be apparent. A supply pipe 42 is connected at one end to the valve 41 and at its opposite end with a suitable source of fluid pressure supply such as a compressed air tank.
- 75 A collar 43 surrounds the plunger adjacent its upper end and is secured thereto in any suitable manner. This collar is provided 80 with outstanding portions 44 having vertical webs 45 formed at their outer ends. A pair of supporting arms 46 are arranged as shown in Figure 2 of the drawings. These arms may be formed of channel irons, I-beams 85 or the like and are provided with central parallel portions 47 bolted to the webs 45 as at 48. Outwardly of the parallel portions 47, the arms are provided with diverging portions 49 which are arranged substantially 90 radially of the plunger as clearly shown in Figure 2. The arms 46 terminate at their outer ends in parallel portions 50 which are secured by rivets or the like 51 to vehicle supporting rails 52. It will be apparent that 95 these rails may be made in any suitable shape, and in the present instance they are illustrated as angle irons having vertical portions 53 through which the rivets 51 pass, and horizontal portions 54 which normally contact 100 with the surface of the concrete 13 and are adapted to directly support the vehicle. The outer ends of the vertical portions of the rails may be turned outwardly as at 55 to prevent 105 the ends of the vertical portions from contacting with the tires of motor vehicles driven upon the rails. In order to positively prevent the outer ends of the arms 46 from sagging under the weight of a vehicle, a steel plate 56 is arranged over the upper end of 110 the plunger and is riveted or otherwise secured to the parallel portions of the arms as at 57.
- 115 The oil may be inserted in the plunger and cylinder through an opening normally closed by a plug 58. The oil is adapted to be used for lubricating purposes such as lubricating the springs and other parts of the vehicle in position on the rails when the device is in elevated position. For this purpose I provide a pipe 59 extending downwardly into the plunger a substantial distance and secured at its upper end to the head 30. The oil is adapted to flow into the lower end 120 of the pipe and the flow of oil through the pipe is controlled by a manually operable valve 60. A hose 61 is connected to the valve 60 and is provided with a control valve 62 at its outer end. A spray nozzle or the like 63 is secured to the valve 62.
- 125 130

It will be noted that the sleeve 22 is relatively long, and the sleeve is of course polished on its outer surface to form a sliding fit with the interior of the cylinder. This 5 sleeve is provided with an upper end 64 which is machined and polished to a smooth surface and is adapted to contact with the lower end 65 of the bearing 15 when the plunger is in elevated position. The lower 10 end 65 of the bearing 15 is also machined and polished, and when the lower face of the bearing contacts with the upper end of the sleeve 22 these elements act in effect as a valve for a purpose to be described.

15 The operation of the device is as follows:

As previously stated, the rails are adapted to rest upon the surface of the ground or surrounding concrete and a vehicle may be driven thereon when in such position. It is 20 very difficult to provide a concrete surface which is perfectly smooth, and hence one or more ends of the rails may not perfectly seat upon the surrounding surface. When a vehicle is driven upon the rails, there is a tendency 25 therefore for the portions of the rails which do not seat tightly upon the surrounding surface to sag downwardly thus transmitting this sagging movement to the plunger. The elongated bearing surface of 30 the sleeve 22 prevents any distortion of the plunger, thus serving to maintain it in properly centered position within the cylinder and eliminating any tendency of the bearing 15 to wear unevenly. It also will be noted that 35 the arms 46 are secured against the inner portions of the rails, and consequently the surrounding surface of concrete is relatively flat throughout and no pit is necessary to receive the supporting arms or other portions of the 40 apparatus when the plunger is in lower position. When it is desired to elevate the device, the valve 40 is closed and the valve 41 is opened thus permitting fluid pressure to flow 45 through the several piping connections to the interior of the plunger above the level of the oil therein. The fluid pressure elevates the plunger, as will be obvious, and as the plunger is elevated, the oil flows through the space within the cylindrical portion 26 of the thimble 25, and through the openings 29 and the 50 space between the cylindrical portion 26 and the opening 24. These oil passages permit the oil to flow downwardly freely and substantially unrestricted, whereby the device 55 may be readily elevated with a minimum pressure. While the device is in elevated position, any desired work may be performed beneath the vehicle, as will be apparent. The springs and other parts of the vehicle 60 may be oiled by opening the valve 60, and the operator may directly control the spraying of the oil through nozzle 63 by manually controlling the valve 62. It will be apparent 65 that the delivery of oil to the nozzle 63 is dependent upon the presence of fluid pres-

sure within the cylinder and plunger, and accordingly if the valves 60 and 62 are opened by unauthorized persons when the plunger is in lowered position, no oil will be delivered from the nozzle 63. When it is desired 70 to lower the device, the valve 41 is closed and the valve 40 opened, thus permitting air to escape from the interior of the plunger. When this action takes place, it will be apparent 75 that there is greater pressure beneath the plunger head 23 than in the interior of the plunger and consequently the thimble 25 will be elevated and the flange 27 will contact with the head 23. This action prevents oil from flowing upwardly through the openings 29, the oil merely flowing through the restricted space provided between the pipe 32 and the cylindrical portion of the thimble. Thus the plunger will be lowered slowly, and since the same differential pressure will exist 80 within the cylinder and plunger if the valve 40 is inadvertently opened, or if the pipe line breaks, it will be apparent that the dash pot action of the thimble 25 allows ample time 85 for an operator to shift his position when the plunger starts downwardly.

When fluid pressure is admitted to the interior of the plunger, movement of the plunger upwardly will continue, until the upper end of the sleeve 22 contacts with the lower end of the bearing 15. The contacting surfaces of these elements are polished, as previously stated, and act in effect as a valve to prevent the passage of oil upwardly into 90 the bearing 15. Thus it will be apparent that the packing 18 is subjected to pressure only while the device is being elevated, and is relieved from pressure as soon as the plunger reaches its uppermost position.

The structure disclosed permits the plunger to be withdrawn from the cylinder for the purpose of making repairs, without removing the entire cylinder from the concrete well. In order to remove the plunger, the upper plunger head, supporting arms and rails are 100 detached from the plunger and the bolts 20 are removed, thus permitting the removal of the gland 19. Sufficient concrete is then removed to provide access to the bolts 17, 105 whereupon the bearing 15 may be lifted upwardly and removed from the plunger. Since the inside diameter of the cylinder is 110 constant throughout its length, it will be apparent that the piston may be drawn upwardly and removed from the cylinder.

The welding of the sleeve 22 to the plunger and the similar means employed for securing heads 11 and 23 in position permits the use of threaded connections to be eliminated 115 whereby the device more cheaply may be manufactured and wherein the parts are more securely fixed to each other.

It is to be understood that the form of the invention herewith shown and described is 120 to be taken as a preferred example of the 125

same and that various changes in the shape, size and arrangement of parts may be resorted to without departing from the spirit of the invention or the scope of the subjoined claims.

I claim:

1. An automobile servicing lift comprising an upright cylinder adapted to be embedded in the ground with its upper end substantially at ground level, a plunger slidably and rotatably fitting the cylinder and with its upper end above ground level when in lowered position, a pair of parallel vehicle supporting rails located on opposite sides of the plunger, each rail having a horizontal vehicle engaging portion and a vertical portion, a head member secured to the plunger at its upper end, arms projecting horizontally outward from the head and having their outer ends attached to the vertical portions of the rails, and means for effecting the elevation and lowering of the plunger.
2. An automobile servicing lift comprising an upright cylinder adapted to be embedded in the ground, a plunger fitting the cylinder for longitudinal and horizontal rotational movements and having its upper end projecting from the cylinder when in lowermost position, a pair of parallel vehicle supporting rails located on opposite sides of the plunger, a head on the upper end of the plunger, arms projecting horizontally from the head and to which the rails are attached substantially in the horizontal plane of the head and arms, and means for effecting elevation and lowering of the plunger.
3. An automobile servicing lift comprising an upright cylinder adapted to be embedded in the ground with its upper end substantially at ground level, a plunger fitting the cylinder for longitudinal and rotary movements and having its upper end projecting above the cylinder when the plunger is down, a pair of parallel vehicle supporting rails located on opposite sides of the plunger, a support attached to the upper end of the plunger and joined to the rails in substantially the plane of the support attachment to the plunger, and means for effecting the elevation and lowering of the plunger.
4. An automobile servicing lift comprising an upright cylinder adapted to be embedded in the ground, a plunger slidably and rotatably fitting the cylinder and in its lowermost position having its upper end exposed above ground level, a support secured to the exposed end of the plunger and extending horizontally outward therefrom, a pair of vehicle supporting rails located on opposite sides of the plunger and attached thereto by the support in substantially the horizontal plane of the support, and means for effecting the elevation and lowering of the plunger.

55 In testimony whereof I affix my signature.
PETER J. LUNATI
